T. G. MASON.

ELECTRICALLY CONTROLLED ELEVATOR.

APPLICATION FILED DEC. 10, 1910.

1,091,003.

Patented Mar. 24, 1914.

UNITED STATES PATENT OFFICE.

THOMAS GABRIEL MASON, OF TORONTO, ONTARIO, CANADA.

ELECTRICALLY-CONTROLLED ELEVATOR.

1,091,003.

Specification of Letters Patent. Patented Mar. 24, 1914.

Application filed December 10, 1910. Serial No. 596,671.

To all whom it may concern:

Be it known that I, THOMAS GABRIEL MASON, of the city of Toronto, in the county of York, in the Province of Ontario, Canada, have invented certain new and useful Improvements in Electrically-Controlled Elevators, of which the following is the specification.

My invention relates to improvements in 10 electrically controlled elevators and the object of the invention is to devise an electric control which will dispense with a car operator and enable anyone desiring to use the car to bring it to any desired floor, and by 15 which it may be located and brought to any desired floor merely by the operation of a designated push button by which the user has absolute and individual control for the time being of the car until he reaches the 20 floor, and by which sufficient time is allowed to open the door to enter.

It consists of a series of push buttons one located at each floor, a series of push buttons in the car, contacts between the car gate 25 and frame, a circuit breaking switch, a time closure controlling the closing of the switch, a floor selecting device a main wire leading from the car operating mechanism through the push buttons of the car, through the circuit breaking switch, gate contacts, each of 30 the floor push buttons, through the time controlling device to the selecting device from which lead wires for the up and down 35 circuits as hereinafter more particularly explained by the following specification.

The drawing represents a view of my device partially in section and partially in diagram.

A, B, C and D are the floors provided with 40 gates A', A'', A''' and A''. The gates are provided with contact plates 1, 2, 3 and 4. The frame of each gate is provided with contacts 1', 1'' which are bridged by the contact plates 1, 2, 3 and 4 of the gates.

45 B is the car provided with a series of push buttons B', B'', B''' and B'''' and a circuit opening button B⁵.

E E' E'' and E''' are the floor push buttons.

F is a knife switch. The knife of the 50 switch is secured to a rocking arbor F' journaled in suitable bearings. The arbor F' is provided with an arm F'' on which is supported a counterweight F''. The arbor F' is also provided with a series of arms F⁴, F⁵, 55 F⁶ and F⁷.

G', G², G³ and G⁴ are a series of solenoids each provided with a slot G' through which the arms F⁴, F⁵, F⁶ and F⁷ extend.

H, H', H² and H³ are contact plates connected to wires 5, 6, 7 and 8 leading to the solenoid coils G', G², G³ and G⁴.

H⁴, H⁵, H⁶ and H⁷ are contact plates opposing the contact plates H, H', H² and H³.

I is a gear connected to the arbor F' by a ratchet and pawl I' and I² respectively.

I³ is a fan mounted upon a suitable shaft I⁴ and connected by train of gear I⁵ to the gear I.

9 is the down wire, 10 the up wire and 11 the main wire, leading to the usual car operating mechanism.

12, 13, 14 and 15 are plates connected to the up wire 10.

16, 17, 18 and 19 are plates connected to the down wire 9.

20, 21, 22, and 23 are spaces intervening between the plates 16 and 17, 18 and 19 and the plates 12, 13, 14 and 15.

24, 25, 26 and 27 are brushes which travel along the plates 12, 13, and 14, and 15, and 20 the plates 16, 17, 18 and 19 in unison with the rise and the fall of the car.

24', 25', 26' and 27' are wires leading from the brushes 24, 25, and 26 to the solenoid coils G', G², G³ and G⁴.

28, 29 and 30 and 31 are wires leading from the wires 5, 6, 7, and 8 to the floor push buttons E, E', E² and E³.

32 are wires leading from the contact plates 1² of one floor to the contact plates 1' of the floor below. The upper contact plate 1' is connected by a wire 33 to the push button E² of the lowermost floor. The wire 33 is connected by branch wires 34, 35 and 36 to the floor push button E, E' and E² of the intermediate floors. The lowermost contact plate 1² is connected by the wire 37 to one terminal of the knife switch F. 38 is a wire leading from the other terminal of the knife switch to the plates 100 H', H², H³, H⁴ by branch wires 39, 40, 41, 42.

43, 44, 45, 46 are wires leading from the push buttons B', B'', B''' and B'''' to the wires 8, 7, 6 and 5.

B¹¹, B¹² and B¹³ are a supplemental series 110

of push buttons connected by wires B^6 and branch wires B^8 , B^9 and B^{10} to the main wires 11, and by wires B^{15} , B^{16} , and B^{17} to the wires 43, 44, 45. Although I show the buttons, B^{11} , B^{12} and B^{13} at the floor A it will of course be understood that a similar set of buttons will be located at the floors B, C and D.

Having described the principal parts involved in my invention I will briefly describe the operation of the same. It will be understood that before the circuit can be completed to operate the car all the gate contacts 1, 1' and 1² must be closed and also the circuit breaking button B^5 and knife switch F. It will be noticed from the drawing that the car is located at the top floor. If it is desired to bring the car to the bottom floor I press the push button E^3 corresponding to that floor. The circuit is then completed through the main wire 11, wire 11', wire 38, knife switch F, wire 37 to the lowermost contact plate 1² from whence it passes through all the gate contacts to the wire 33 leading to the push button E^3 . The circuit extends from the push button E^3 by wire 31 to the solenoid coil G^4 connected by wire 27' to the brush 27, thence by the plate 19 to the down wire 9. Immediately the solenoid G^4 is energized the core thereof rises connecting the contact plates H^7 and H^3 , opening the knife switch by means of the rock shaft and raising the weight F^3 . By the rise of the core of the solenoid G^4 the contacts H^7 and H^3 are connected together so that the circuit passes from the wire 11' through the contacts H^7 and H^3 through the solenoid coil to the brush 27 by the wire 27'. By this means it will be seen that all the floor push buttons are short circuited rendering them inoperative and preventing the operation of the car by any other push button than the one pressed. It will also be seen that if any of the gates are open the circuit is broken between the plates 1 and the plates 1' and 1² thereby also preventing the operation of the car. After the push button E^3 has been pressed the car descends to the bottom floor the brush 27 moving down the strip or plate 19 until it reaches the opening 23. When the brush 27 reaches the opening 23 the circuit of the solenoid G^4 is broken and the weight F^3 moves the knife switch slowly to the circuit closing position being retarded by the fan I^3 . The time it takes for the weight to descend is regulated by the fan I^3 which is driven by the descending weight. The slow closing of the knife switch allows time for the user of the car to open the gate and enter the car. This mechanism is provided to allow for a definite time to elapse between the stopping of the car and its being started again by the operation of one of the push buttons on any

of the floors. Once the door is opened the car of course cannot be controlled by any of the push buttons until the door is closed. The device does not operate to close the door but only to allow a predetermined interval to elapse in which the circuit is controlled by the knife switch F between the time that the car stops and the breaking of the circuit by the opening of the door thereby rendering it impossible to interfere with the car by the pressing of any other push button while the door is being opened. The user may then operate the car by means of push buttons B^1 , B^2 , B^3 and B^4 . If the user desires to go to the top floor from any other floor he presses the push button B^4 thereby completing the circuit from the main wire 11 through the push button B^5 , thence by wire 11', push button B^4 , wire 46 to the solenoid G^4 . From the solenoid G^4 the circuit passes by the wire 24' to the brush 24 in contact with the strip 12 connected to the up wire 10. If it is desired to stop the car at any point intermediately between the floors the circuit may be opened by pressing the circuit opening button B^5 . By pressing one of the supplemental buttons B^{11} , B^{12} or B^{13} a circuit is closed through the floor selecting device so as to carry the car to the corresponding floor B, C or D. At the floors B, C and D the same device may be employed to carry the car to any desired floor. It will be understood that such of the gates are provided with suitable counterweights so that they will automatically close when released so as to close the contacts 1', 1².

From this description it will be seen that I have devised a very simple device whereby the car may be controlled so as to bring it to any desired floor and at the same time prevent the car being affected by more than one push button and in which means is also provided whereby it is impossible to operate the car should any of the gates be open and in which also I have provided a controlling device wherein the car mechanism is rendered inoperative by any push button for a short period to give sufficient time for opening the elevator gate. Of course it will be understood that this device may be attached to any car which has already been installed or which may be installed.

What I claim as my invention is:

In a controlling device for electric elevators comprising a push button located at each floor in proximity to the elevator shaft, an electric circuit comprising the main feed wire leading through the elevator shaft, the up and down wires, branch wires leading from the main feed wire through the push button to the up and down wires, a switch connection for cutting the push buttons out of circuit, immediately after the

car has started into motion, and comprising a knife switch, a rock shaft on which the knife of the switch is mounted, a counter balancing arm and weight connected to the rock shaft, an electric magnetic means for raising the weight up on one of the push buttons being pressed, and a retarding fan mounted on the shaft, and designed to control the gradual descent of the weight, as and for the purpose specified.

THOMAS GABRIEL MASON.
